By Rudolph J. Foy, Atty.

UNITED STATES PATENT OFFICE.

THOMAS OLIVER, OF CHICAGO, ILLINOIS.

VENDING-MACHINE.

No. 918,584.

Specification of Letters Patent.

Patented April 20, 1909.

Application filed May 2, 1908. Serial No. 430,468.

To all whom it may concern:

Be it known that I, THOMAS OLIVER, a citizen of the United States, residing at Chicago, in the county of Cook and State of Illinois, have invented certain new and useful Improvements in Vending-Machines; and I do hereby declare the following to be a full, clear, and exact description of the invention, such as will enable others skilled in the art to which it appertains to make and use the same.

This invention relates to a novel construction in a vending machine, the object being to provide a device of this character which is simple and durable, and in which the mechanism is both simple and positive.

The invention consists in the features of construction and combinations of parts hereinafter fully described and claimed.

In the accompanying drawings illustrating my invention: Figure 1 is a central vertical section of a vending machine constructed in accordance with my invention. Figs. 2 and 3 are plan sections of the same on the lines 2-2 and 3-3 respectively of Fig. 1. Fig. 4 is a fragmentary detail vertical section on the line 4-4 of Fig. 2. Fig. 5 is a fragmentary detail section showing part of the operating mechanism. Fig. 6 is a fragmentary detail central vertical section on an enlarged scale on the line 6-6 of Fig. 5.

My said invention has for its main object to provide operating mechanism which very simple and cheap, can not readily get out of order and which is easily finished, assembled and operated.

The specifically novel features of the invention will be particularly pointed out in the following specification and claims.

The device comprises the base 1 of any suitable form on which the reservoir 2 for the matter to be vended, such as shelled nuts, is suitably secured and supported. The said reservoir 2 is preferably cylindrical and double walled, there being an annular space 3 between the concentric walls thereof which serves as insulating space to enable said nuts to be maintained hot by suitably disposing heating apparatus in the base 1, said heating apparatus being omitted from illustration.

The bottom plate 4 of the reservoir 2 is provided with a central opening bordered by an annular upwardly extend-

ing flange 5 on which the dispensing member 6 rotates. The latter consists of a relatively flat cylindrical plate provided in its periphery with recesses 7 constituting pockets in which the nuts are received, said pockets being adapted to successively register with a recess 8 in said bottom plate 4 to drop their contents into a cup 9 to be delivered to the purchaser. The hub portion of said plate 6 is provided with radial slots 10 corresponding in number and relative location with said recesses 7, the walls of said slots being beveled at their inner ends for reasons which will hereafter appear. Said hub portion is also annularly cut away at the bottom as at 11 to render the same about one-half as thick as the outer portion of said plate. A free annular space is thus provided around the base of said flange 5 in which an inverted L-shaped segmental plate 12 is received, the latter being secured to said flange and forming a stop for coins as will be hereinafter described. The said flange 5 is peripherally cut away at two points 13 and 14 in which dogs 15 and 16 are disposed, the said dog 15 consisting of a flat spring secured at one end to said flange 5 and at its free end bearing upon the wall of the central opening of the plate 6. The dog 16 is pivotally secured to said flange 5 and also bears at its free end upon the wall of the central opening of said plate 6, being actuated by the spring 17. Both said dogs are adapted to enter the V-shaped mouths of the radial slots 10 and when both said dogs are so disposed said plate 6 is held against rotation in either directions, said dogs being relatively oppositely disposed in such positions as to simultaneously enter two of said V-shaped mouths of said slots 10. Secured within said flange 5 is a section 18 of tubing constituting a flange of smaller diameter than said flange 5 and which may obviously be integral with the latter. Pivotally mounted on said flange 18 is the hub 19 of the operating lever 20 which carries the coin chute 21, said lever at its free end passing through suitable slots in the walls of the reservoir 2. Said coin chute 21 is adapted to register at its delivery end with a radial slot 10 of the plate 6, the hub portion of the latter being of less

thickness than the diameter of the coin of specified denomination to be used. The said lever — 20 — is maintained by a spring — 22 — at one limit of its movement, the latter being determined by any suitable stop such as the end wall of the slot through which said lever projects, and when at said limit of its movement the delivery end of the coin chute registers with one of said slots — 10 —, the latter being at this time disposed over the stop — 12 — so that the deposited coin constitutes a clutch for operatively connecting the plate — 6 — with said lever — 20 —. The latter is equipped on its hub portion with a downwardly extending projection — 23 — which when said lever is at the normal limit of its movement engages the free end portion of the dog — 16 — to throw the latter out of engagement with said plate — 6 —. After depositing the coin the lever — 20 — is turned, thus rotating the plate — 6 — therewith. During the initial movement of said lever — 20 — the said projection — 23 — releases the dog — 16 — but by the time that the latter is fully released the V-shaped recess last entered by its free end will have passed and said free end will thus bear upon the wall of the central opening of said plate — 6 — and enter the next succeeding recess, thus preventing said plate — 6 — from being rotated through more than the predetermined arc and thereby preventing the contents of more than one pocket — 7 — being discharged for each coin deposited. As the said lever — 20 — reaches the other limit of its movement the deposited coin passes beyond the other end of the stop — 12 — and drops through the chute — 24 — into the cash box — 25 —. The lever — 20 — when released returns to its normal position and unless a coin is deposited may be rocked freely without actuating said plate — 6 —. A partition wall — 26 — is disposed in the reservoir — 2 — and covers said operating mechanism above described with the exception of a portion of said plate — 6 —, several pockets of the latter remaining exposed to receive nuts from the reservoir. Said partition wall is of a peculiar shape, comprising a semi-conical portion — 27 — bordered by flat flanges — 28 — extending radially to the inner wall of the reservoir, the top portion of said wall being inclined to cause nuts to pass from the same into the lowest portion of said reservoir and into the pockets — 7 —. The latter in passing for a considerable period through the reservoir become well filled with nuts and insure delivery of an accurately measured quantity to the purchaser. The lower end of one of the flat flanges — 28 — is equipped with a sharp edge which serves to cut projecting portions of nuts to prevent undue resistance to operation of the machine as will be obvious.

I believe that the dispensing member 6 provided with coin slots which serve also substantially as ratchet teeth is novel as is also the specific operative connection of the lever — 20 — therewith, though I am aware 70 that generically the mechanism described is not novel.

I claim as my invention:

1. In a vending machine, a rotating member equipped with pockets adapted to consecutively receive and discharge matter to be vended, there being radially disposed slots in the said member through which coins are adapted to pass into a coin receptacle, locking means disposed in operative relation to 80 said member to lock same against rotation in either direction, a pivoted lever equipped with a coin slot adapted to register with one of said slots of said rotating member when said lever is at one limit of its movement, a spring normally maintaining said lever at 85 said limit of its movement, a stop disposed in the path of the coin below said rotating member, said coin when resting on said stop serving as a means preventing relative rotation of said member and said lever, and means carried by said lever and engaging said locking means when at the normal limit of its movement to release said rotating member. 90

2. In a vending machine, a carrier provided with a coin slot, a lever normally loose with relation to said carrier, said lever having a coin slot therein and being adapted to be clutched against movement relatively to 100 said carrier by the deposited coin, means normally holding said carrier against movement, and means controlled by said lever normally releasing said carrier holding means. 105

3. In a vending machine, a carrier provided with a coin slot, a lever normally loose with relation to said carrier, said lever having a coin slot therein and being adapted to be clutched against movement relatively to 110 said carrier by the deposited coin, means normally holding said carrier against movement, and means carried by said lever normally releasing said carrier holding means.

4. In a vending machine, the combination 115 with a movable carrier provided with a coin slot and means normally holding said carrier against movement in any direction, of a lever equipped with a coin slot normally loose with relation to said carrier and adapted to be clutched rigid with the latter by the deposited coin and means controlled by said lever and operatively engaging said carrier holding means to normally release the latter to permit movement of said carrier in one 120 direction. 125

5. In a vending machine, the combination with a movable carrier provided with a coin slot and means normally holding said carrier against movement in any direction, of a 130

lever equipped with a coin slot normally loose with relation to said carrier and adapted to be clutched rigid with the latter by the deposited coin and means carried by said lever and operatively engaging said carrier holding means to normally release the latter to permit movement of said carrier in one direction.

6. In a vending machine, the combination 10 with a movable carrier provided with a coin slot and means normally holding said carrier against movement in any direction, of a lever equipped with a coin slot normally loose with relation to said carrier and adapted to 15 be clutched rigid with the latter by the deposited coin a spring maintaining said lever at one limit of its movement, and means controlled by said lever and operatively engaging said carrier holding means to normally 20 release the latter to permit movement of said carrier in one direction.

7. In a vending machine, the combination 25 with a movable carrier provided with a coin slot and means normally holding said carrier against movement in any direction, of a lever equipped with a coin slot normally loose with relation to said carrier and adapted to be clutched rigid with the latter by the deposited coin a spring maintaining said lever 30 at one limit of its movement and means carried by said lever and operatively engaging said carrier holding means to normally release the latter to permit movement of said carrier in one direction.

35 8. In a vending machine, a carrier equipped with a coin slot for the passage of coins, coin arresting means disposed in operative relation to said carrier to prevent the passage of coins through said coin slot, a 40 lever equipped with a coin slot and normally maintained at one limit of its movement by a spring, the deposited coin serving to prevent relative movement of said lever and said carrier, means normally holding said carrier 45 against movement in either direction, and means actuated by said lever and operatively

engaging said carrier holding means to maintain said carrier normally free to move in one direction.

9. In a vending machine, a carrier 50 equipped with a coin slot for the passage of coins, coin arresting means disposed in operative relation to said carrier to prevent the passage of coins through said coin slot, a lever equipped with a coin slot and normally 55 maintained at one limit of its movement by a spring, the deposited coin serving to prevent relative movement of said lever and said carrier, means normally holding said carrier against movement in either direction, and 60 means carried by said lever and operatively engaging said carrier holding means to maintain said carrier normally free to move in one direction.

10. In a vending machine, a rotating carrier 65 equipped in its hub portion with coin slots for the passage of coins, coin supporting means disposed below said hub portion and preventing the passage of coins during a given arc of movement of said carrier, a 70 lever equipped with a coin slot normally loose with relation to said carrier and a spring normally maintaining said lever at one limit of its movement, the deposited coin serving to hold said lever and said carrier 75 against relative movement, recesses in the wall of the central opening in said carrier dogs normally engaging the walls of said recesses to hold said carrier against movement in either direction, and means actuated by 80 said lever and operatively engaging one of said dogs to normally maintain the latter out of engagement with said carrier whereby the latter is free to move in one direction.

In testimony whereof I have signed my 85 name in the presence of two subscribing witnesses.

THOMAS OLIVER.
